Patented Sept. 3, 1918.

Inventor
Corydon Weston

UNITED STATES PATENT OFFICE.

CORYDON W. SEXTON, OF WAYNESBORO, PENNSYLVANIA.

DEVICE FOR UTILIZING WASTED HEAT.

1,278,035.

Specification of Letters Patent.

Patented Sept. 3, 1918.

Application filed February 20, 1918. Serial No. 218,228.

To all whom it may concern:

Be it known that I, CORYDON W. SEXTON, a citizen of the United States, residing at Waynesboro, in the county of Franklin and State of Pennsylvania, have invented a new and useful Improvement in Devices for Utilizing Wasted Heat, of which the following is a specification.

My invention is designed to utilize for heating purposes the waste gases escaping into chimneys, stacks or flues from stoves, ranges, furnaces and other heating apparatus.

The invention consists in a tubular heating drum, so called for lack of a better name, interposed in the smoke pipe or flue of a heating apparatus, through which the smoke is circulated in connection with air currents before it is allowed to escape finally; the drum being so arranged or located as to serve as a heater, as hereinafter explained and claimed.

In the accompanying drawings illustrating the invention, in the several figures of which like parts are similarly designated, Figure 1 is a side elevation, partly in section at the top, and Fig. 2 is a partly mutilated top plan view of one form of heater.

I have illustrated only one form of heater embodying the principle and modes of operation of my invention, and it is here noted that variations are deemed to be within the spirit and scope of the invention and included in the claims hereinafter made.

In the construction shown, the drum is composed of an outer closed box 1, of suitable material, and an inner shell 2 arranged within the box and spaced apart therefrom on all sides. The outer box has an arched or other suitable top 3, which, if desired, may be removable. In this top is the longitudinally arranged smoke-flue or pipe 4 having the damper 5 arranged transversely therein just beyond a collar 6 which affords communication between the smoke-flue and the interior of the shell 2.

The shell 2 is provided with a series of vertically disposed air-tubes 7 which open at the top into an inside hood 8 and at the bottom into the space between the inner shell and the outer box. The smoke-flue or pipe 4 also extends through this hood 8. The interior of the shell is further divided into any number of compartments by means of baffle plates 9 and 10 preferably extending

alternately from the top and bottom of the shell so that the waste gases, smoke, or products of combustion entering the shell through the collar 6 circulate around the tubes 7 in one compartment and thence under the baffle 60 plate 9 into the next compartment and around its tubes and thence over the baffle plate 10 into the next compartment and around its tubes and finally escape through the tube 11 into the extension 12 of the 65 smoke-flue 4, and so on to the chimney, stack or other flue.

13 is a pipe entering the top of the outer box or casing and communicating with the space therein between said box and the inner shell to supply atmospheric air to the air tubes 7 of the inner shell, and 14 is a smaller pipe within pipe 13 opening into the hood 8. This hood receives the air admitted through pipe 13 and heated by means 70 of the waste gases within the apparatus as the air passes up through the air-tubes 7 into the hood, and from this hood the thus heated air may be conducted to a distant place for distribution through a register or 75 other means for heating purposes.

It will be seen that otherwise wasted heat of a heating apparatus of any kind may be efficiently utilized for heating air that may be distributed either by radiation from the 80 auxiliary heater or conducted therefrom to a distant point.

In the construction shown the damper admits of being turned so as to permit the smoke or waste gases to pass directly 90 through the apparatus without circulation whenever that is desired.

By the means described a very simple and economical apparatus is provided for utilizing the waste gases from various kinds of 95 domestic and other heaters.

What I claim is:—

1. A device for utilizing wasted heat, comprising an outer box, an inner shell arranged within said box and spaced apart 100 therefrom on all sides and having a hood at its top, said shell provided with air tubes opening at opposite ends respectively into the hood and the bottom space between the box and shell, means to introduce heated 105 gases into said shell, and means to provide for the escape of the gases from said shell when the heat is spent.

2. A device for utilizing wasted heat, comprising an outer box, an inner shell ar- 110

ranged within said box and spaced apart therefrom on all sides and having a hood at its top, said shell provided with air tubes opening into the bottom space and hood 5 at opposite ends, and baffle plates interposed between said air tubes to compel circulation around the same, means to introduce heated gases into said shell, and means to provide for the escape of such gases from said shell 10 when the heat is spent.

3. A device for utilizing wasted heat, comprising an outer box, an inner shell arranged within said box and spaced apart therefrom on all sides and having a hood 15 at its top, said shell provided with air tubes opening at opposite ends respectively into the hood and the bottom space between the box and shell, means to introduce atmospheric air into the space surrounding the 20 shell, means to introduce heated gases into said shell to heat the air so introduced, means opening into the hood to convey away the heated air for useful purposes, and

means to provide for the escape of the gases from said shell when the heat is spent. 25

4. A device for utilizing wasted heat, comprising an outer box, an inner shell arranged within said box and spaced apart therefrom, means to introduce air into said space, said shell provided with air tubes 30 opening into said space at one end, a hood mounted over the inner shell into which the other ends of said air tubes open, and baffle plates interposed between said air tubes to compel circulation around the same, a pipe 35 arranged across the apparatus within the hood and communicating with the interior of the shell to introduce the heated gases into said shell, and means to provide for the escape from the shell of the spent waste 40 gases.

CORYDON W. SEXTON.
